ELECTRIC WAVING IRON

Lelia Iles Francis, Dayton, Ohio

Application June 27, 1944, Serial No. 542,395

4 Claims.

(Cl. 132—31)

This invention relates to electric hair curling or waving irons of the scissor type in which an oscillating or vibrating leg operates in conjunction with a stationary leg to bring about the desired wave or curl in the hair.

The primary object of the present invention is to provide a novel and efficient hair waving iron of the above type having simple and efficient means for rapidly vibrating the oscillating leg and in which said means is mounted in and completely enclosed by a hollow handle of the stationary leg, said means being operatively connected to the handle of the vibrating leg within said handle of the stationary leg.

Another object of the present invention is to provide simple and efficient means for manually swinging the vibrating leg to and retaining the same in a position spaced from the stationary leg to facilitate engagement of the hair with the iron or disengagement of the iron from the hair.

Other objects and features of the invention will become apparent from the following description when considered in connection with the accompanying drawing, and the invention consists in the novel form, combination and arrangement of parts hereinafter more fully described, shown in the drawing and claimed.

In the drawing, wherein like reference characters indicate corresponding parts throughout the several views:

Figure 1 is a substantially central longitudinal sectional view of a hair curling or waving iron constructed in accordance with the present invention.

Figure 2 is a fragmentary longitudinal section taken substantially upon line 2—2 of Figure 1.

Figure 3 is a transverse section taken on line 3—3 of Figure 1.

Referring in detail to the drawing, the present electric vibrating hair curling or waving iron comprises a cylindrical vibrating leg 5 and a stationary trough-shaped leg 6 pivoted to each other in scissor-like fashion, as at 7, the stationary leg 6 being provided with a relatively large elongated hollow handle 8 preferably formed of heat insulating and electrical insulating material. The forward portion of the handle 8 has a longitudinal slot 9 in one side thereof within which is vibratable a shorter shank-like handle 10 of the vibrating leg 5.

Suitably mounted at 11 within the inner portion of the handle 8 is the coil 12 of a solenoid having a core 13 reciprocable parallel with the longitudinal axis of the waving iron, said core being normally projected forwardly by a spring

14 and being attractable rearwardly when the coil 12 is energized. Pivotedly mounted at the juncture of its arms, as at 15, at the side of the handle 8 opposite the slot 9 and in front of the solenoid, is a bell crank lever 16 having a longer arm extending transversely of the handle 8 directly in front of the coil 12 and pivotally connected at 17 intermediate its ends with the forward end of the core 13. The spring 14 is coiled about the pivot 15 of lever 16 and has one end thereof bearing upon the handle 8 and the other end of the same engaged in a lug 18 provided on one side of the longer arm of lever 16. The other shorter arm of lever 16 extends forwardly from the pivot 15 and is operatively connected by a connecting bar 19 with the inner end of the handle 10. Suitably mounted at 20 directly in front of the free end portion of the transverse longer arm of lever 16 is a normally closed circuit maker and breaker which includes a stationary contact 21 and a resilient flexible contact 22, the latter being arranged to be intermittently contacted by the longer arm of lever 16 as the latter is vibrated by the reciprocation of solenoid core 13 for rapidly opening and closing the circuit of the coil 12 by moving the contact 22 into engagement with contact 21 and then permitting contact 22 to flex and disengage from said contact 21. The contacts 21 and 22 are interposed in the circuit of the coil 12, as is also a manually operable switch 23 suitably mounted in one side of the handle 8. An adjusting screw 24 is arranged to impinge the free end of contact 22, and may be adjusted to effect a micromatic adjustment of contact 22 relative to the contact 21 so as to control the frequency of vibration of the solenoid core 13 and consequently of the vibrating leg 5 of the waving iron. At the inner end of the handle 8 there is provided an opening in which is swiveled a connector 25 to which the line wires 26 extend. Wires 26 connect contacts of this connector with the switch 23 and one side of the coil 12. The wires 26 may be those of an ordinary attachment cord adapted to be plugged into an outlet receptacle of an ordinary house wiring system so as to derive current for operation of the iron.

From the above description, it will be evident that the spring 14 normally positions the lever 16 so that its longer arm positions contact 22 into engagement with contact 21 so as to close the circuit of the coil 12 at this point. Thus, when switch 23 is closed, the coil 12 is energized and the core 13 of the solenoid is caused to rapidly reciprocate in accordance with well known

principles of operation of electric vibrators. Such rapid reciprocation of core 13 causes rapid oscillation of lever 16 and, through connection 19 with handle 10, the leg 5 of the iron is rapidly vibrated. The use of a curling or waving iron of this type is well known in the art, as well as its manner of use in bringing about the necessary wave or curl in the hair.

If desired, the cylindrical vibrating leg 5 may be provided with an internal electrical heating element generally indicated by dotted lines at 27, thereby avoiding the necessity of heating the leg 5 by an extraneous or outside source of heat. As shown, this electrical heating element may be connected with the wires 26 so as to derive current as soon as the attachment plug, of which the wires 26 form a part, is engaged in an outlet receptacle. Of course, a switch may be provided for controlling the flow of current from wires 26 to the heating element 27 if desired.

As shown clearly in Figure 1, the shorter forwardly projecting arm of lever 16 is provided on its outer side with a cam lug 28, and slidably mounted in a slot 29 in the adjacent side of handle 8 is a finger piece or slide 30 having a ball or similar contact element 31 arranged to ride on the inclined surface of cam 28 when the slide 30 is shifted forwardly. The arrangement is such that when the slide 30 is shifted forwardly, the contact element 31 rides under the cam lug 28 so as to swing lever 16 in a direction to actuate handle 10 and move the vibrating leg 5 to and retain the same in a position separated from the leg 6. When this is done, engagement of the hair with the iron or disengagement of the iron from the hair is facilitated, the switch 23 being of course turned off at this time. On the other hand, when the slide 30 is shifted rearwardly so as to move the contact element 31 from beneath the cam lug 28, the lever 16 is free to be electrically vibrated by the solenoid when the switch 23 is turned on.

From the foregoing description, it will be seen that I have provided a very simple, compact, durable and efficient hair curling or waving arm of the type described which is convenient and easy to use, capable of being easily and cheaply manufactured and assembled, and otherwise well adapted to meet with the requirements for a successful commercial use. Minor changes in details of construction illustrated and described are contemplated, such as fairly fall within the spirit of the invention as claimed.

What I claim is:

1. An electric vibrating hair waving iron of the character described comprising, in combination, a vibrating leg and a stationary leg pivoted to each other in scissors-like fashion, a hollow elongated handle on the stationary leg having a longitudinal slot in the forward portion thereof, a shank-like shorter handle on the vibrating leg movable in the slot of the first-named handle, an electrical vibrator mounted in said first-named handle and including a solenoid having a core reciprocable longitudinally of the curling iron and retractable rearwardly of the latter, yieldable means for normally projecting the core of the solenoid forwardly of the curling iron, a bell crank lever pivoted in the first-named handle and having an arm extending transversely of the latter and pivotally connected intermediate its ends to the forward end of the solenoid core, said bell crank lever having a second arm extending forwardly at the side of the first-named handle opposite the handle of the vibrating leg, and a

transverse connecting rod between the last-named arm of the bell crank lever and the handle of the vibrating leg.

2. An electric vibrating hair waving iron of the character described comprising, in combination, a vibrating leg and a stationary leg pivoted to each other in scissors-like fashion, a hollow elongated handle on the stationary leg having a longitudinal slot in the forward portion thereof, a shank-like shorter handle on the vibrating leg movable in the slot of the first-named handle, an electrical vibrator mounted in said first-named handle and including a solenoid having a core reciprocable longitudinally of the curling iron and retractable rearwardly of the latter, yieldable means for normally projecting the core of the solenoid forwardly of the curling iron, a bell crank lever pivoted in the first-named handle and having an arm extending transversely of the latter and pivotally connected intermediate its ends to the forward end of the solenoid core, said bell crank lever having a second arm extending forwardly at the side of the first-named handle opposite the handle of the vibrating leg, and a transverse connecting rod between the last-named arm of the bell crank lever and the handle of the vibrating leg, said vibrator including a normally closed circuit maker and breaker for the coil of the solenoid arranged directly in front of the first-named arm of the bell crank lever and including a stationary contact and a flexible resilient contact tensioned to disengage from said stationary contact, said flexible contact being arranged to be intermittently engaged by the first-named arm of the bell crank lever when the latter is vibrated by actuation of the solenoid core for intermittently making and breaking the circuit of said solenoid magnet.
3. An electric vibrating hair waving iron of the character described comprising, in combination, a vibrating leg and a stationary leg pivoted to each other in scissors-like fashion, a hollow elongated handle on the stationary leg having a longitudinal slot in the forward portion thereof, a shank-like shorter handle on the vibrating leg movable in the slot of the first-named handle, an electrical vibrator mounted in said first-named handle and including a solenoid having a core reciprocable longitudinally of the curling iron and retractable rearwardly of the latter, yieldable means for normally projecting the core of the solenoid forwardly of the curling iron, a bell crank lever pivoted in the first-named handle and having an arm extending transversely of the latter and pivotally connected intermediate its ends to the forward end of the solenoid core, said bell crank lever having a second arm extending forwardly at the side of the first-named handle opposite the handle of the vibrating leg, and a transverse connecting rod between the last-named arm of the bell crank lever and the handle of the vibrating leg, said vibrator including a normally closed circuit maker and breaker for the coil of the solenoid arranged directly in front of the first-named arm of the bell crank lever and including a stationary contact and a flexible resilient contact tensioned to disengage from said stationary contact, said flexible contact being arranged to be intermittently engaged by the first-named arm of the bell crank lever when the latter is vibrated by actuation of the solenoid core for intermittently making and breaking the circuit of said solenoid magnet, and an adjusting screw for effecting micromatic adjustment of the flexible contact of the circuit

maker and breaker to vary the frequency of vibration of the solenoid core and the frequency of vibration of the vibrating leg thereby.

4. An electric vibrating hair waving iron of the character described comprising, in combination, a vibrating leg and a stationary leg pivoted to each other in scissors-like fashion, a hollow elongated handle on the stationary leg having a longitudinal slot in the forward portion thereof, a shank-like shorter handle on the vibrating leg movable in the slot of the first-named handle, an electrical vibrator mounted in said first-named handle and including a solenoid having a core reciprocable longitudinally of the curling iron and retractable rearwardly of the latter, yieldable means for normally projecting the core of the solenoid forwardly of the curling iron, a bell crank lever pivoted in the first-named handle

5 and having an arm extending transversely of the latter and pivotally connected intermediate its ends to the forward end of the solenoid core, said bell crank lever having a second arm extending forwardly at the side of the first-named handle opposite the handle of the vibrating leg, and a transverse connecting rod between the last-named arm of the bell crank lever and the handle of the vibrating leg, the second-named leg 10 of the bell crank lever having a cam lug on the outer side thereof, a slide mounted in one side of the first-named handle and having a contact element movable under said cam lug to swing the bell crank lever in a direction to move the vibrating leg to and retain the same in a position spaced from the stationary leg.

LELIA ILES FRANCIS.
